AUTOLoADING FIREARM

Allen A. Dicke, Montclair, N. J.

Application November 2, 1940, Serial No. 363,961

18 Claims.

(Cl. 42—3)

This invention relates to autoloading firearms whether of the small arms type such as automatic pistols, autoloading rifles, sub-machine guns, or machine guns, or of the larger type generally designated as ordnance, and has for an object to improve such devices by assuring that the breech closing mechanism will remain fully closed until the gas pressure has dropped to a certain predetermined value.

Another object is to form the chamber walls 10 relatively thin and surround said chamber with a relatively thick collar associated with the breech closing mechanism, so that at the instant of explosion the chamber will expand against the enclosing collar and hold it in position (whether against axial or rotary movement), thereby preventing opening of the breech mechanism until the gas pressure has dropped to a certain point.

A more specific object is to provide such a construction in which the supporting collar is directly connected with the breech block for longitudinal movement therewith, said collar and the connected breech block being temporarily held in position against such axial movement.

Another object is to provide a device in which 25 the enclosing collar is normally held against axial movement but is free to rotate, said collar being provided with an abutment co-acting with an axially movable non-rotatable breech block by means of lugs or interrupted threads thereon, or equivalent co-acting means, whereby the block is held in closed position while the gas pressure is sufficiently high so that the expanded chamber holds the collar against rotation but that when the gas pressure drops and the chamber contracts, the collar is rotated through rearward axial movement of the breech block.

Another object of the invention is to provide a device in which the enclosing collar is normally held against axial movement but is free to rotate, said collar being provided with a rearward extension engaging with a rotatable breech bolt so that rotation and opening of the breech bolt is prevented until the gas pressure has dropped to a certain point.

Further objects and advantages of this invention will be apparent from consideration of the specification as illustrated by the accompanying drawings of possible embodiments of the invention, in which drawings:

Fig. 1 is a longitudinal vertical cross-sectional view of a portion of a firearm illustrating one form the invention may take;

Fig. 2 shows an explosion gas pressure-time curve of a normal cartridge and similar curves

for abnormally high pressure and abnormally low pressure cartridges.

Fig. 3 is a horizontal cross-sectional view of a portion of the receiver and barrel parts of another firearm illustrating the invention;

Fig. 4 is a view, partly in vertical cross-section, of the arm shown in Fig. 3;

Fig. 5 is a cross-section taken on the line 5—5 of Fig. 3;

Fig. 6 is a cross-section taken on the line 6—6 of Fig. 3;

Fig. 7 is a cross-section taken on the line 7—7 of Fig. 4;

Fig. 8 is a vertical cross-sectional view of a part of another firearm illustrating the invention;

Fig. 9 is a horizontal cross-sectional view of the arm shown in Fig. 8;

Fig. 10 is a cross-sectional view taken on the line 10—10 of Fig. 8; and

Fig. 11 illustrates another modification.

Referring to Fig. 1, the numeral 11 designates the barrel having a chamber 11a to receive the cartridge 12. It will be noted that a portion 11b of said chamber is reduced in outside diameter. The barrel 11 is shown threaded to the receiver 13 as at 11c. In the form shown, the receiver has a passage 13a which may be either round or rectangular in cross-section, within which 30 passage is located for axial movement the breech block 14 having integrally formed therewith a forwardly extending collar 14a which surrounds and fits rather closely upon the expandable portion 11b of the chamber. The breech block 14 is 35 biased forwardly by means of spring 15 bearing against an abutment, such as the closing screw 16.

It will be seen that when the cartridge 12 is fired, by any suitable firing mechanism not illustrated, the gas pressure will rise rapidly, as shown in Fig. 2, causing the expandable chamber 11b to expand slightly (possibly .0005 to .002 inch), gripping the collar 14a and preventing the opening of the breech. This condition continues 45 until the gas pressure has dropped to a certain point as, for example, the value indicated by the line a—a (Fig. 2). When this point is reached (point y) the chamber part 11b contracts, due to its natural resiliency, and frees the collar 14a, 50 whereupon the breech block 14 is driven rearwardly, due to the residual pressure compressing spring 15.

For convenience in ejecting the fired cartridge case, the breech block is preferably formed as shown, i. e., the breech block contains a bolt 17

consisting of a cylindrical head portion 17a whose forward end bears against the base of the cartridge, and a reduced extension 17b, the said bolt lying in a correspondingly formed bore in the breech block 14, its movement being limited 5 as by means of a cross pin 18 located in the cut-out 17c.

It will be noted that the closing screw 16 is formed with a forward extension 16a in line with the bolt portion 17b. Therefore, as the breech block 14 is driven rearwardly by the remaining gas pressure acting through bolt head 17a, the bolt and block will move back together until the fired case has been withdrawn from the chamber, (assisted if necessary by extractor 17d preferably carried by the bolt head 17a). Thereafter, bolt 17 is arrested by the extension 16a, whereas the block 14 continues to travel to the end of its movement (the parts now are in the dotted line position of Fig. 1). At this time, ejection of the case by suitable known means (not shown) is effected. During subsequent forward movement of the breech block 14, a new cartridge, such as the one indicated at 12a, is pushed forwardly into the chamber. The firing mechanism having been retracted during the excursion of the bolt, the gun has been completely and automatically re-loaded and upon release of the firing mechanism, whether automatically or by another pull of the trigger, the arm will again fire and the cycle be repeated.

In the form shown in Figs. 3 to 7 inclusive, the numeral 21 represents the barrel threaded to the receiver 23 as at 21c. The barrel is formed with a chamber 21a, a portion of which 21b, is reduced in external diameter. The chamber is closed by means of a breech block 24 shown as attached to a tube 24a slidably mounted in a passage 23a in the receiver. This passage may be either round or rectangular, as the bolt 24 and tube 24a are 40 not adapted to rotate.

25 indicates a handle slidable in a slot 25a in the side of the receiver. This handle may be used to operate the action manually when desired and may also serve the purpose of preventing rotation of the bolt. The forward end of the bolt 24 is provided with lugs 26 and 26a.

The reduced expandible portion 21b of the chamber is surrounded by a collar 27 fitting loosely thereon and confined axially between a shoulder on the barrel and the shoulder 28 in the receiver. The collar 27 has a rearward extension 29 formed with helical passages 29a within which the lugs 26, 26a, normally fit, it being apparent from Fig. 3 that the front and rear faces of said lugs have a corresponding helical form. Connected with said passages 29a are entrance passages 29b located generally horizontally (see Figs. 4 and 6).

In the form shown, the action spring 30 is located in the receiver with its forward end within the tube 23a, which spring tends to push the bolt forward tightly against the head of the cartridge 22 within the chamber.

It will be noted that the helix angle of the passages 29a and the faces of the lugs 26 and 26a is so great that axial movement of the bolt will cause rotation of the collar 27, 29. It will therefore be noted that if the handle 25 is pulled rearwardly, the lugs 26 and 26a will cause rotation of the collar 27, 29 clockwise, as viewed from the rear, to an extent of 90° in the form shown, at which time the entrance passages 29b align with said lugs, and the bolt may be freely drawn rearwardly. During this time the unfired car-

tridge in the chamber, if any, is extracted by means of any suitable extractor carried by the bolt 24 (shown in cross-section and indicated by the numeral 24b in Fig. 5).

If the gun is closed with a cartridge 22 in the chamber and the firing mechanism (striker or firing pin) is actuated, the cartridge will be exploded, resulting in a powerful rearward thrust against the bolt 24. However, at the same time, 10 the reduced chamber portion 21b is slightly expanded, grasping the collar 27 and holding it against rotation. It will therefore be impossible for the lugs to move rearwardly and the bolt will remain in closed position until the gas pressure 15 has dropped to a predetermined value, such as that represented by the line a—a in Fig. 2. When this point is reached, the chamber part 21b contracts, releasing collar 27. The residual powder pressure is sufficient, however, to thrust the bolt 24 rearwardly. In so doing, the lugs cause rotation through 90° of the collar 27, 29, thus locating the entrance passages 29b vertically, permitting the lugs 26, 26a, to pass rearwardly, whereby the bolt 24 and its carrying tube 24a 25 may move rearwardly the full distance (somewhat greater than the length of the cartridge), while storing energy in the compression of spring 30.

Immediately thereafter, the bolt parts are 30 pushed forwardly, pushing the next cartridge 22a upwardly and forwardly into the chamber. In the form shown, the bullet passes up through the entrance slot 29b. When the bolt has almost reached its forward limit of movement, the lugs 26, 26a, pass in through the entrance slots 29b until their forward edges strike the helical front surface of the passage 29a, rotating the collar 27, 29 counterclockwise, as viewed from the rear, thus closing the action.

The numeral 31 designates a plunger biased upwardly by spring 32 and bearing normally in a recess 27a in the collar 27. It will be noted from Fig. 7, that the plunger does not normally enter fully within recess 27a but bears only on one side thereof so as to tend to rotate the collar 27 counterclockwise, as viewed from the rear. This serves to take up any slack which might be present between the helical faces of the lugs 26 and 26a and the helical passage 29a, and will also serve to assure that the collar 27 will be pressed firmly against abutment shoulder 28. This construction assures minimum head space and play.

The collar 27 is formed with another depression 27b slightly more than 90° from the depression 27a. When the gun is opened, whether by hand or as a result of firing, depression 27b aligns with the plunger 31 and assures that the collar 27, 29 will be held in proper position so that the entrance openings 29b will be vertically arranged and in proper alignment with the lugs 26, 26a.

Any suitable firing mechanism may be employed such as a striker 35 biased forwardly by a spring (not shown). The rear end of said striker is shown as formed with an arm 36 with which is engageable the hook 37 of a sear 38 biased clockwise by spring 39. The sear is shown as provided with a pin 38a with which engages a shoulder 40a on a disconnector bar 40 pivotally connected at 41a with the trigger 41. Trigger spring 42 serves to rock the trigger clockwise. The disconnector bar 40 is shown as having an upwardly extending finger 40b lying in the path 70 of a part of the breech block tube 24a. As will

be readily understood, when firing occurs and the breech block moves rearwardly, it strikes the finger 40b and rocks the disconnector bar 40 clockwise against the action of spring 40c, thus permitting the sear to spring back into effective position even though the shooter continues to hold the trigger retracted. Therefore, as the breech block is pushed forwardly the hook 37 engages with the arm 36 and holds the striker back in position ready for firing the next cartridge.

Operation

If the magazine, which may be a box magazine, tubular magazine, cartridge belt, or cartridge drum, is filled with cartridges and the handle 25 drawn rearwardly, the collar 27, 29 will rotate clockwise about 90°, releasing the lugs 26, 26a, and permitting the breech block to be retracted the full limit of its movement against the action of spring 30. Thereupon, by usual means, the first cartridge in the magazine is placed in position for insertion into the chamber. By releasing handle 25, this cartridge is pushed forwardly into the chamber. During this movement, the lugs 26, 26a pass through the now vertically disposed entrance passages 29b and thereupon rotate the collar 27, 29 about 90° counter clockwise, due to the co-action of the helical surfaces on the lugs and on the collar 29. As the bolt reaches its forward limit of movement with its face against the head of the cartridge in the chamber, the plunger 31 snaps into recess 27a, thus rotating the collar 27, 29 slightly counter clockwise, assuring that the collar 27 bears firmly against abutment 28 and that the collar 29 bears firmly against the rear faces of lugs 26, 26a, thus eliminating play and excessive head space.

If the trigger is now pulled, the striker 35 is released and the cartridge exploded. This immediately causes a slight expansion of the thin section 21b of the chamber, thus holding the collar 27 against rotation. As a result of which, lugs 26, 26a cannot move rearwardly and the action remains closed. This condition continues until the gas pressure has dropped to a predetermined point, say that represented by line a—a in Fig. 2, i. e., at the point y for the normal cartridge represented by the full line curve. At this point, the chamber part 21b contracts, freeing collar 27 which now rotates about 90° clockwise under the thrust of the remaining gas pressure, thus freeing the breech block for its rearward excursion, during which extraction and ejection occur. On its forward excursion, the breech block pushes the next cartridge into the chamber, the bullet thereof in the form shown passing up through one of the entrance slots 29b. As the breech block reaches its forward limit of movement, the collar 27, 29 is again rotated counter clockwise about 90° to its normal locking position. This cycle of operation can of course be repeated as long as cartridges are available in the magazine.

In addition to its great simplicity and cheapness, an advantage of this construction is that the gun will reload reliably even in spite of variations in the power of the ammunition used. It is well known that it is very difficult to load cartridges uniformly and that even though this is accomplished the cartridges will, upon long storage, deteriorate thus causing unequal gas pressures.

Fig. 2 indicates in full line the pressure-time

curve of a normal cartridge whereas the dotted lines represent respectively the pressure-time curve of low powered and high powered cartridges. Assuming that the gun in question is set to open at a pressure of 1,000 units, when the normal cartridge is used the opening will occur after about 33 units of time. If, however, a weak cartridge is used, the gun opens at the point x, namely, after about 27 units of time and with a powerful cartridge the gun opens at z, namely, after about 39 units of time. As the gas pressure when the gun opens is the same irrespective of the power of the cartridge, it is obvious that the same pressure and force will be available to operate the action. This is directly contrary to the experience with gas operated guns which open earlier for high power cartridges and later for low power cartridges, the direct opposite of the desired action.

Another form illustrative of the invention is shown in Figs. 8, 9, and 10, wherein the breech closing mechanism is of the rotary bolt type. The bolt may be similar to that of any high power bolt action rifle, such as the Springfield model of 1903, with the exception that the lug faces and their co-acting abutments within the receiver are of helical conformation, the helix angle being slightly greater than the angle of repose. In the form shown the barrel 21 may be of the same construction as that shown in Figs. 3 and 4. The chamber supporting collar 57 differs however in that it does not support the thrust of the bolt but has extensions 57a and 57b which co-act with and prevent rotation of the lugs 56 and 56a of the bolt 54 when the collar 57 is held against rotation by excessive gas pressure. The bolt 54 may be carried, as shown, by a tubular member 54a within which the action spring 58 is housed. The bolt lugs are in normal position located between lugs 53a and 53b, preferably forming an integral part of the receiver 53. A plunger 31 actuated by spring 32 is preferably employed to hold the collar 57 in its desired rotative position. As in the case of the form shown, in Figs. 3 to 7 inclusive, the plunger preferably rests within its depressions in such a way as to eliminate play between the extensions 57a and 57b and the lugs 56 and 56a.

Operation

When firing occurs, the rearward thrust against the bolt 54 tends to cause rotation of the bolt due to the helical surfaces on the rear lug faces and the cooperating lugs 53a in the receiver. However, rotation is prevented by the extensions 57a and 57b of the collar 57, which is held in place by the expansion of the chamber. The breech therefore remains closed until the gas pressure drops to a point where the chamber portion 21b contracts, freeing the collar 57 and permitting the action to open. During this time, the collar 57 is rotated about 90°. On the rearward excursion of the bolt, extraction and ejection occur by usual means not shown and on the return stroke, the next cartridge 22a is pushed into the chamber, the bullet thereof being moved forwardly and upwardly through the space between extensions 57a and 57b which are now arranged generally vertically. When the bolt is almost home, the front faces of lugs 56 and 56a strike cooperating inclined surfaces 53b on the receiver, thus causing rotation of the bolt to its locking position, carrying collar 57 along. The gun is now ready to be fired again, which cycle

may be repeated indefinitely as long as ammunition is available.

The dimensions of the reduced chamber section as shown in the drawings are not intended to be accurate for all purposes. The wall thickness 5 would be computed according to the power of the cartridge and the gas pressure at which opening is desired.

As guns of this type frequently are fired many times in quick succession, the barrel including its chamber portion is likely to become heated to a rather high temperature. Likewise, collar 14a, 21, or 57 will also become heated but probably not to the same temperature. This might result in expansion of the chamber relative to the collar to an undesired extent. To overcome this possible difficulty, it is proposed to make the supporting collar of a material having a higher thermal coefficient of expansion than the steel used for the barrel. For this purpose the use of certain stainless steels known to have a high expansion coefficient is contemplated.

Fig. 11 is a cross-section through the chamber of a gun of any of the illustrated types illustrating a modified form. Instead of depending upon the expansion of the chamber to grip the supporting collar (as 14a, 21, or 57), the chamber wall 21x may be made considerably thicker and the supporting collar 21x somewhat thinner. The chamber wall 21x is perforated to receive a plunger 21y having its ends formed concentric with the barrel bore. When the gun is fired, the plunger 21y will be shifted very slightly, its outer end being thrust against the collar 21x and holding it against movement until the gas pressure subsides to a certain value. If desired, the plunger may be formed shouldered as shown with a washer 21z of rubber or the like to provide slight resiliency and to assure proper sealing.

It will be noted that in the forms shown in Figs. 3 to 10 inclusive, the thrust on the block 24 or bolt 54 can cause rotation of the collar 21, 29, or 57, 57a, only through a negative mechanical advantage, this being due to the fact that the helix angles are so chosen as to be only slightly greater than the angle of repose. Therefore, only a slight gripping of the collar by the expansible chamber will suffice to prevent opening of the action.

It is, of course, to be understood that various supplemental devices may be used, such as safety devices, single shot or automatic-fire firing mechanism, means for holding the action open when the magazine is empty, barrel cooling means, etc.

The invention is not intended to be limited to the several forms of construction shown, which are to be understood as illustrative only and not as limiting as various changes in construction and arrangement may be made, it being intended that the patent shall cover by suitable expression in the appended claims all features of patentable novelty existing in the invention disclosed.

I claim:

1. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a supporting member closely surrounding said reduced portion, a breech closing member, and means associated with said supporting member preventing opening of the breech closing member while the reduced chamber portion is expanded against said surrounding sup-

porting member, whereby the breech closing member is held closed until after the gas pressure has dropped sufficiently low to permit contraction of the weakened chamber portion.

2. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a supporting collar closely surrounding said reduced portion, a breech closing member, and means associated with said supporting member preventing opening of the breech closing member while the reduced chamber portion is expanded against said supporting collar, whereby the breech closing member is held closed until after the gas pressure has dropped sufficiently low to permit contraction of the weakened chamber portion and freeing of said collar.

3. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a rotatable supporting collar closely surrounding said reduced portion, a breech closing member, and means associated with said rotatable supporting collar preventing opening of the breech closing member without rotating said collar, whereby the breech closing member is held closed until after the gas pressure has dropped sufficiently low to permit contraction of the weakened chamber portion and rotation of said collar.

4. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a rotatable supporting collar closely surrounding said reduced portion, a non-rotatable breech closing member, and helical connecting means between said breech closing member and said collar whereby the breech closing member is held closed until after the gas pressure has dropped sufficiently low to permit contraction of the weakened chamber portion and rotation of said collar.

5. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a receiver, a rotatable supporting collar closely surrounding said reduced portion, a rotatable breech closing member, and helical connecting means between said breech closing member and said receiver, means connected with the supporting collar for preventing rotation of said breech closing member without rotating said supporting collar, whereby the breech closing member is held closed until after the gas pressure has dropped sufficiently low to permit contraction of the weakened chamber portion and consequent rotation of said collar and said rotatable breech closing member.

6. The combination according to claim 3 including detent means for holding the supporting collar in its normal rotative position.

7. The combination according to claim 4 in-

- cluding detent means for holding the supporting collar in its normal rotative position.
8. The combination according to claim 5 including detent means for holding the supporting collar in its normal rotative position.
9. The combination according to claim 3 including detent means for holding the supporting collar either in its normal position or in the breech openable position.
10. The combination according to claim 4 including detent means for holding the supporting collar either in its normal position or in breech openable position.
11. The combination according to claim 5 including detent means for holding the supporting collar either in its normal position or in breech openable position.
12. The combination according to claim 3 including detent means for holding the supporting collar in its normal rotative position but biased to closed breech position.
13. The combination according to claim 4 including detent means for holding the supporting collar in its normal rotative position but biased to closed breech position.
14. The combination according to claim 5 including detent means for holding the supporting collar in its normal rotative position but biased to closed breech position.
15. In a firearm, a barrel having a cartridge receiving chamber formed therein, at least a part of the chamber portion of said barrel being formed as a tube of such reduced thickness that the gas pressure of a cartridge exploded in said chamber is capable of expanding the said reduced chamber portion, a breech closing member formed with a collar closely surrounding said reduced portion, whereby the breech closing member is held closed until after the gas pressure has dropped sufficiently low to permit contraction of the weakened chamber portion and freeing of said collar.
16. The combination according to claim 1 in which the supporting member is made of a material having a higher co-efficient of thermal expansion than the material of said chamber.
17. In a firearm, a barrel having a cartridge receiving chamber, at least a portion of the chamber being of such reduced thickness that the gas pressure of a cartridge exploded in said chamber is capable of expanding the said reduced chamber portion, a supporting member closely surrounding said reduced portion, said reduced chamber portion and said surrounding member being normally relatively movable, a breech closing member, and means so associated with said supporting member that opening of the breech closing member will cause relative movement between the surrounding supporting member and the reduced chamber portion, whereby opening of the breech closing member is prevented while the reduced chamber portion is expanded against said supporting member so that the breech closing member is held closed until after the gas pressure has dropped sufficiently low to permit contraction of the weakened chamber portion.
18. In a firearm, a barrel having a cartridge receiving chamber, at least a portion of the chamber being of such reduced thickness that the gas pressure of a cartridge exploded in said chamber is capable of expanding the said reduced chamber portion, a supporting member closely surrounding said reduced portion, said reduced chamber portion and said surrounding member being normally relatively rotatable, a breech closing member, and means so associated with said supporting member that opening of the breech closing member will cause relative rotation between the surrounding supporting member and the reduced chamber portion, whereby opening of the breech closing member is prevented while the reduced chamber portion is expanded against said supporting member so that the breech closing member is held closed until after the gas pressure has dropped sufficiently low to permit contraction of the weakened chamber portion.
